UNITED STATES PATENT OFFICE.

CHARLES FISHER, OF OAK PARK, ILLINOIS, ASSIGNOR, BY MESNE ASSIGNMENTS, TO THE AUTOMATIC RECORDING SAFE COMPANY, OF CHICAGO, ILLINOIS, A CORPORATION OF ILLINOIS.

PORTABLE SAVINGS-BANK.

1,010,881.

Specification of Letters Patent.

Patented Dec. 5, 1911.

Application filed October 22, 1906. Serial No. 339,913.

To all whom it may concern:

Be it known that I, CHARLES FISHER, a citizen of the United States, residing at Oak Park, in the county of Cook and State 5 of Illinois, have invented certain new and useful Improvements in Portable Savings-Banks, of which the following is a specification, reference being had to the accompanying drawing, forming a part thereof.

10 The main objects of this invention are to provide a portable receptacle of strong, simple and durable construction into which money can be readily introduced but from which it cannot be removed without a key 15 or without unlocking and opening the receptacle, and generally to improve the construction and operation of devices of this character.

It consists in certain novel features of 20 construction and in the peculiar arrangement and combination of parts as herein-after particularly described and defined in the claims.

In the accompanying drawing like characters 25 designate the same parts in the several figures.

Figure 1 is a plan view of a bank embodying the present invention, a portion of the cover or removable closure being broken 30 away; Fig. 2 is a vertical section of the bank on the lines 2 2, Figs. 1 and 3; Fig. 3 is an inverted plan or inside view of the cover or closure removed from the body or coin receptacle, and Fig. 4 is a vertical section of 35 the bank on the line 4 4, Fig. 3, in a plane at right angles to the section of Fig. 2.

Although the bank is intended to stand in an inverted position upon its cover or removable closure, as shown in Fig. 4, in the 40 following description the cover will be regarded as the top of the bank as it is shown in Fig. 2 in position for receiving coins.

Banks of the class to which this invention relates are designed to be supplied by banking 45 houses to small depositors to induce them to start and keep savings accounts and thus encourage and form the habit of saving, keys for opening the banks being usually kept in the custody of the depositaries 50 with whom accounts are kept.

The bank is composed of two main parts, a body or coin receptacle *a*, and a cover or removable closure *b*. The body *a* is preferably drawn or stamped in cylindrical form 55 from sheet metal. On the open side or end

it is formed with an inturned marginal flange *c*. The cover *b*, which may be conveniently made of cast metal, is preferably of circular shape and is formed on the under or inner side with a circular flange *d* which fits loosely inside of the flange *c* on the body, the rim *e* of the cover overlapping the flange *c*. On one side the cover is formed with a lug *f* adapted to project underneath and engage with the flange *c*, and on the opposite side it is provided with a lock or fastening for detachably securing it to said flange. This lock or fastening may consist, as shown in Figs. 2 and 3, of a bolt 60 *g* fitted in a socket, in the cover, and adapted to be retracted against the tension of a spring *h* by a key inserted in and turned with a slotted barrel or guide *i* which is fitted in a socket in the cover at one side of and transverse to the bolt socket. The bolt 65 is retained in the socket and its endwise movement therein is limited by a screw *j*, the point of which projects into a notch or recess in one side of the bolt, as shown in Fig. 2. On its upper or outer side the cover 70 is formed with a depressed inclined coin guide *k* leading to the lower side of a slot *l*. A second guide *m* attached to the inner or under side of the cover, inclined in a reverse direction and extending, when the bank is 75 closed, from one side of the body *a*, back underneath the guide *k*, forms a reversed conduit for coins inserted through the slot *l*, a space or opening between the lower end 80 of the guide *m* and the overhanging lower end of the guide *k* being left for the passage 85 of the coins from said conduit into the bank. 90

Adjacent to its lower edge the guide *m* is formed with a transverse series of pockets *n* in each of which is loosely confined a ball 95 or gravity stop *o* of sufficient size to close or obstruct the space or opening between said guides without escaping through it when the bank is inverted, as shown in Fig. 4, or is tilted or shaken so as to cause the 100 balls or stops to fall or to be thrown by their momentum across or into said space or opening.

The guide *k* is preferably formed on the under side opposite the pockets *n* with a 105 transverse channel or recess *p*.

To provide for the insertion of bills or paper money into the bank and to prevent their withdrawal therefrom without unlocking and removing the cover, an opening *q* 110

is made through the cover and this opening is surrounded on the inner or under side by a flange *r* which terminates in a sharp edge, as shown in Fig. 4.

- 5 To introduce coins or paper money the bank is held in the position in which it is shown in Fig. 2, and the coins placed flatwise on the guide *k* are thrust through the slot *l* upon the guide *m* from which they are
 10 shaken or slid by tilting the bank into the body or receptacle *a* through the space or opening between the two guides. When they are once within the receptacle *a* they cannot be withdrawn therefrom without unlocking
 15 and removing the cover *b*. Any attempt to remove them through the opening between the two guides by inverting, tilting or shaking the bank will be defeated by the balls or gravity stops *o* rolling or being thrown
 20 into or across said opening, and thus preventing the outward passage of the coins through it.

To introduce paper money into the bank the bill is rolled or folded into a sufficiently
 25 compact form to pass through the opening *q*, and when it is completely within the receptacle *a* it will unroll or unfold sufficiently to prevent its withdrawal through said opening around or over the sharp inwardly projecting flange *r*.

I claim.

1. A portable savings bank, comprising a coin receptacle, an external inclined supporting guide at the lower end of which there is
 35 a slot, an internal guide inclining in the opposite direction to the external guide and terminating below the external guide in a slot opening into the coin receptacle and located to one side of the slot at the terminus
 40 of the external guide, and a loose gravitating stop located between the external and internal guides adjacent to the terminus of the internal guide, substantially as described.
 45 2. A portable savings bank comprising a coin receptacle, a member formed with a slot for insertion of a coin and having a

recess on its under side, an internal supporting-guide extending across the aforementioned slot and terminating in a slot opening into the coin receptacle beneath said member, said guide being formed with a pocket adjacent to its end and opposite the recess in said member, and a loose gravitating stop seated in said pocket and adapted to be projected into the recess in the oppositely disposed member, substantially as described. 50

3. A portable savings bank comprising a coin receptacle, a member formed with a slot for insertion of a coin, an internal inclined supporting-guide extending across the aforementioned slot and terminating in a slot opening into the coin receptacle beneath said member, said guide being formed 60 with a series of pockets arranged side by side transversely across the guide adjacent to its end and beneath the oppositely disposed member, and balls loosely confined in the pockets and adapted to be projected 65 toward the oppositely disposed member, substantially as described.

4. A portable savings bank comprising a coin receptacle, a member formed with a slot for insertion of a coin and having a transversely extending channel in its under side, an internal inclined supporting-guide 75 extending across the aforementioned slot and terminating in a slot opening into the coin receptacle beneath said member, said guide being formed with a series of pockets arranged across the guide adjacent to its end and opposite to the channel in the oppositely disposed member, and a ball fitting loosely 80 in each pocket and adapted to be projected 85 into the channel in the oppositely disposed member, substantially as described.

In witness whereof I hereto affix my signature in presence of two witnesses.

CHARLES FISHER.
